ATTORNEY

UNITED STATES PATENT OFFICE.

CHARLES O. YALE, OF NEW YORK, N. Y.

BURGLAR-PROOF VAULT.

SPECIFICATION forming part of Letters Patent No. 416,700, dated December 3, 1889.

Application filed May 25, 1889. Serial No. 312,138. (No model.)

To all whom it may concern:

Be it known that I, CHARLES O. YALE, of the city, county, and State of New York, have invented, made, and applied to use certain new and useful Improvements in Burglar-Proof Vaults, whereof the following is a specification, reference being had to the drawing annexed, showing a perspective view of a vault in course of construction.

10 My improved vault is inclosed by walls, floor, and roof, each in three divisions—viz., a wall of laid-up interlocking railroad "T"-rails, outside of this a wall of protected masonry, and inside a wall or lining of welded iron and steel.

15 To enable others skilled in the art to practice my invention, I will proceed to describe the same.

The vault is begun by first preparing a 20 foundation A, of masonry, and the wall B, of railroad-rails C, is erected thereon. This wall is substantially like that secured to me by Patent No. 169,938, dated November 16, 1875, to which patent I refer for a full description 25 of this part or feature. While this wall is in course of construction it is followed up with the mason-work wall D on the exterior. Prior to my invention the latter have been 30 built of brick and mortar, and hence offer no special impediment to removal for clandestine entrance to the vault.

To provide a barrier for protecting the wall 35 against attempted excavation thereof for access therethrough, I prepare bars E, of welded iron and steel, adapted to lie in and form part of the wall, these bars being also carried continuously around the corners. The bars are arranged in one or more lines side by side in the mortar and cement, as indicated in the 40 drawing, and are repeated every second or third course of bricks. I prefer to arrange them in the interior of the masonry D, so as to be quite out of sight and present no indi-

cation on the exterior surface of their presence. These bars serve to protect the wall against 45 burglarious operations by so increasing the difficulty of penetrating the wall as to exhaust the burglar's available time for doing his work. The inner surface of the wall B is composed of the bottoms or bases of the railroad 50 T-rails. Within this is the wall or lining of welded iron and steel, such as used in the construction of burglar-proof safes. This lining preferably comprises a number of sheets of welded steel and iron laid on in 55 courses or layers—that is to say, first a course F of sheets running from top to bottom, and then another series F' on that running around horizontally. Another series F², running vertically, will break joints with the first, and so 60 on to any desired number of courses, all which are secured to each other and to the wall B in any suitable manner.

I claim as my invention—

1. The improvement in burglar - proof 65 vaults, which consists in introducing a series of strong bars of welded iron or steel into the mason-work, such bars being arranged side by side longitudinally of the wall and built therein as the wall is laid up. 70

2. In a burglar-proof vault, the combination of the inner metallic lining and the outer wall of masonry protected and re-enforced with bars of iron or steel embedded into the mason-work. 75

3. The combination, in a burglar - proof vault, of a wall composed of interlocked railroad - rails, an outer wall of mason - work strengthened with bars of iron embedded therein, and an inner wall or lining of welded 80 steel and iron. 85

CHARLES O. YALE.
